UNITED STATES PATENT OFFICE.

LOUIS SCHORPP, OF PHILADELPHIA, PENNSYLVANIA, ASSIGNEE OF ONE-HALF TO
FREDERICK A. BORKEMANN, OF COLLINGSDALE, PENNSYLVANIA.

COLLAPSIBLE DRINKING CUP.

1,426,916.

Specification of Letters Patent. Patented Aug. 22, 1922.

Application filed March 9, 1921. Serial No. 450,995.

To all whom it may concern:

Be it known that I, LOUIS SCHORPP, a citizen of the United States, residing at Philadelphia, in the county of Philadelphia and State of Pennsylvania, have invented certain new and useful Improvements in Collapsible Drinking Cups, of which the following is a specification.

This invention relates to improvements in collapsible drinking cups.

The object of the invention is to provide a cup of novel, simple and efficient construction which may be collapsed into a very small space and be contained in a casing or holder of relatively small dimensions, so that it will occupy little space in a pocket of a person carrying the same when the cup is not in use, and so that it may be readily available for use when desired.

The invention aims to provide a cup which will gradually and automatically assume an open condition for use while being removed from its carrying case, and which will be automatically returned to its collapsed condition by co-operation with its carrying case when it is gently pushed back into the same.

With the foregoing objects in view, the invention consists in the novel construction, combination and arrangement of parts hereinafter described and claimed.

In the accompanying drawings, illustrating my invention:

Figure 1 is a side view of a cup, embodying my invention.

Figure 2 is a bottom view thereof.

Figure 3 is a vertical section thereof.

Figure 4 is a vertical section through a casing for the cup, showing the cup in collapsed condition therein.

Figure 5 is a sectional view of the casing with its cover removed and showing the cup partly inserted in or partly withdrawn therefrom.

Figure 6 is a side view of a modification of the cup.

Figure 7 is a sectional view of a modification of the casing for the cup shown in Fig. 6, showing the cup collapsed therein.

Referring to Figs. 1 to 5, inclusive, of the drawings, 2 designates a cup which may be formed of rubber or any other suitable, water-proof, collapsible material. The cup 2 may be of any appropriate shape and size

for its intended purpose, and, as herein illustrated, it has a tapered or conical form.

The cup 2 is enclosed within a cage comprising an outwardly flared series of yielding arms 3 which normally hold the cup in open condition, as shown in Fig. 1.

The arms 3 are formed of spring wires, two arms to a wire, which cross each other beneath the cup 2, and which are soldered or otherwise suitably secured together beneath the cup. The wires or arms 3 follow the lines of the cup 2 when it is in the open condition, as illustrated in Figs. 1 and 2.

The upper or open end of the cup 2 is secured to the upper ends of the wires or arms 3 by being clamped between the arms and the turned down upper ends 4 thereof. To prevent accidental tearing of the cup 2, pads 5 of suitable material may be interposed between the clamped portions of the upper edge of the cup 2 and the wires or arms 3 clamping the same.

The bottom of the cup 2 which is of relatively small diameter is made much thicker than the remaining portions thereof to receive opposing indentations 6 formed in the lower ends of the wires or arms 3, as a means to hold the bottom of the cup 2 in place within the bottom of the cage formed by the arms, and to prevent its accidental displacement therefrom. When the bottom of the cup 2 is forced into the bottom of the cage formed by the arms 3, the wire indentations 6 compress the bottom of the cup and embed themselves therein.

The cup 2 and the cage enclosing it formed by the spring arms 3 are adapted to be collapsed into a relatively small space, and, when thus collapsed, to be confined within a suitable casing 7 of relatively small dimensions. This casing 7 may be of any suitable shape for its intended purpose, and, as shown in Figs. 4 and 5, it comprises a tubular body 8 closed at its lower end 9 and provided with a removable cap 8^a for closing its upper end.

When the cup is in the collapsed condition, and confined within the casing 7, as shown in Fig. 4, the spring arms 3 are held substantially parallel to each other by the wall of the casing 7 and the body of the cup is held in its folded or collapsed condition within the casing. When the cup is removed from the casing 7, the spring arms 3,

upon being thereby released, automatically return to their normal condition and thereby automatically return the cup to and retain it in its normal or open condition, as 5 shown in Fig. 1.

As the cup 2 is withdrawn from the casing 7, with its upper or open end foremost, the cup 2 and its spring arms 3 will gradually assume the open condition, due to the 10 fact that the cup 2 and its series of spring arms 3 are outwardly flared. Fig. 5, showing the cup partially withdrawn from the casing 7 shows the cup partly open and returning to its normal condition.

15 When the cup is returned to the casing 7, the lower or small end of the cup is first inserted into the open end of the casing, and, thereafter the cup is pushed down into the casing to the position shown in Fig. 4. As 20 the cup is thus pushed into the casing, the flaring spring arms 3 will engage the casing 7 and be thereby gradually forced toward each other until the cup is entirely collapsed within the casing; and, during this operation, the casing 7 receives and folds inwardly or collapses the cup body 2.

It will now be understood that the cup may be readily placed within or removed from the casing, and that, while it is being 30 placed therein, it will be gradually and automatically collapsed by its engagement with the casing, and that while it is being withdrawn from the casing, it will gradually and automatically assume the normal or open 35 condition for use.

One of the spring arms 3 is provided with a projecting handle 10 which may be used to withdraw the cup from and to move it into the casing; and, after it has been placed 40 therein the cover 8^a may be placed upon the open end of the casing to protect the cup.

In the modification shown in Figs. 6 and 7, the cup 11 and casing 12 are the same as shown in Figs. 1 to 5, inclusive, excepting 45 that the handle 10 is omitted and both ends of the casing 12 are open and the lower end of the cup 11 and its spring arms are enclosed within a head 13 which is secured thereto and has an exterior diameter which

is substantially equal to or slightly less than 50 the interior diameter of the casing 12, so that the cup may be inserted into the casing through the open upper end thereof and be withdrawn from the casing through the lower open end thereof, and so that the head 55 13 will close the lower end of the casing when the cup is confined therein.

I claim as my invention:—

1. The combination of a cup of collapsible material, and a plurality of spring arms 60 connected at the lower ends thereof and embracing the cup and normally holding it in open condition and permitting it to be collapsed under pressure, said arms having indentations in the lower portions thereof 65 engaging the lower portion of the cup and holding it in place.

2. The combination of a cup of collapsible material, and spring arms embracing the cup and normally holding it in open condition and permitting it to be collapsed under pressure, said arms having turned down 70 upper ends, and the top of the cup being clamped between said arms and the turned down ends thereof.

3. The combination of a casing having a removable cap, a cup of collapsible material, and a series of yielding arms connected to and carried by the cup and adapted to hold it in open condition when the cup is unconfined, said cup and its arms being adapted to be introduced to and removed from the casing and being held in collapsed condition by the casing when placed therein, said series of arms being outwardly flared to 85 facilitate their introduction to and removal from the casing and being adapted to gradually and automatically open the cup when it is removed from the casing, one of said arms having a handle extending therefrom and inwardly over the cup and projecting beyond the casing and into said cap when the cup is entirely confined within the casing. 90

In testimony whereof I affix my signature 95 hereto.

LOUIS SCHORPP.
